US00D615319S

(12) **United States Design Patent**
Tuszkiewicz et al.

(10) **Patent No.:** **US D615,319 S**
(45) **Date of Patent:** **** May 11, 2010**

(54) **PRODUCT MERCHANTIZING UNIT**

5,561,981 A 10/1996 Quisenberry et al.

(75) Inventors: **George A. Tuszkiewicz**, Plymouth, MN (US); **Mark Bedard**, Greenfield Park, CA (US)

(Continued)

(73) Assignee: **General Mills, Inc.**, Minneapolis, MN (US)

CA 2 462 635 A1 9/2005

(**) Term: **14 Years**

(Continued)

(21) Appl. No.: **29/327,759**

(22) Filed: **Nov. 12, 2008**

(51) **LOC (9) Cl.** **06-04**

(52) **U.S. Cl.** **D6/396**

(58) **Field of Classification Search** D6/396, D6/509, 472, 397, 432, 436, 449, 470, 471, D6/448, 433; D15/81, 83, 84, 79; 62/125, 62/126; 312/3.3, 116, 236, 400-406, 258; D14/307; D21/325

See application file for complete search history.

(57) **CLAIM**

The ornamental design for a product merchandizing unit, as shown and described.

DESCRIPTION

FIG. 1 is a top, right side, and front perspective view of a product merchandizing unit of the present disclosure;

FIG. 2 is a front elevational view thereof;

FIG. 3 is a rear elevational view thereof;

FIG. 4 is a left side elevational view thereof with the right side elevational view being an identical mirror image that is omitted;

FIG. 5 is a top elevational view thereof; and,

FIG. 6 is a bottom elevational view thereof.

The broken lines in the drawings are for illustrative purposes and form no part of the claimed design.
